UNITED STATES PATENT OFFICE.

WILLIAM T. DOREMUS, OF FLATBUSH, NEW YORK.

CHECK, DRAFT, OR OTHER MONEY-ORDER.

SPECIFICATION forming part of Letters Patent No. 325,199, dated August 25, 1885.

Application filed March 11, 1885. (No model.)

To all whom it may concern:

Be it known that I, WILLIAM T. DOREMUS, a resident of Flatbush, in the county of Kings and State of New York, have invented a new 5 and useful Improvement in Checks, Drafts, and other Money-Orders, of which the following is a full, clear, and exact description.

Reference is to be had to the accompanying drawings, forming a part of this specification, 10 in which similar letters of reference indicate corresponding parts in both the figures.

Figure 1 is a plan view of one of my improved checks shown in blank. Fig. 2 is a 15 plan view of the same shown as filled out.

The object of this invention is to provide 20 blank checks, drafts, and other money-orders prepared in such a manner that when properly filled out they cannot be readily raised or made to represent a larger sum than that 25 for which they were drawn.

The invention relates to a check, draft, or 30 other money-order made with spaces to receive the name of the place and the date, the name of the drawee and the order, and the name of the payee, with a space containing groups of 35 three of each of the digits, with two or more spaces to receive a statement of the sum in words, with spaces to receive the signature of the drawer, and with two sets of spaces corresponding therewith, the one set containing 40 the names of the various denominations and the other set to receive numerals representing the amounts of the said various denominations and ciphers, as will be hereinafter fully 45 described and then claimed.

The check is prepared with a space, A, for 50 the name of the place where and the date when the said check is drawn, a space, B, to receive the name of the drawee, and a space, C, to receive the order and the name of the payee. Below the spaces A B C is a space, 55 D, which is divided by short vertical lines into twenty-seven sections, in each of the first three of which is placed the figure 1, in each 60 of the second three is placed the figure 2, and so on through the nine digits. The three spaces of each group correspond with the units, tens, hundreds of the system of notation, and may be distinguished by different 65 colors—as, for instance, red, white, and blue—to catch the eye, or may be left white, as may be desired. Below the space D are two or

more spaces, E, in which the amount for which the check is drawn is to be written in words. Below the spaces E are two groups of spaces, 55 F G, to receive the name of the drawer, and which are separated by a central vertical line. I prefer to use five spaces, F, and four spaces, G, as illustrated in the drawings, but more or less may be used, as desired. At the right hand 60 end of the spaces F are formed, by vertical lines, two sets of spaces, H I. In the spaces H are written the words "thousands," "hundreds," "tens," "units," the fifth space, when used, being left blank. 65

The spaces I are designed to receive numerals and ciphers when filling out the check. At the left hand end of the spaces G are formed, by vertical lines, two sets of spaces, 70 J K. In the spaces J are written the words "millions," "hundreds of thousands," "tens of thousands," the fourth space, when used, being left blank.

In filling out the check the sum for which the said check is drawn is written out in 75 words in the spaces E, beginning under that group the numeral of which represents the amount of the highest denomination mentioned in the sum and under the units, tens, or hundreds of the said group, according as 80 the said highest denomination is units, tens, or hundreds. The signature of the drawer is written in the space F or G, the corresponding space H of which contains the name of the highest denomination mentioned in the 85 sum. The numerals representing the amounts of the several denominations mentioned in the sum are then written into the spaces I or K opposite the names in the spaces H or J of the said several denominations, ciphers being 90 placed in the spaces I and K not occupied by numerals. The sum can then be written in numerals at the bottom of the check.

A check made and filled out in the manner herein described cannot be raised without 95 making so many changes that the attempted fraud will be at once detected. For example, if the sum be seven hundred eighty one seventy-eight one-hundredths dollars, this sum will be written in the spaces E, beginning under the left hand or hundreds 7, hundreds being the highest denomination mentioned and seven being the amount of the said denomination. The beginning would be in the same 100

place were the sum seven hundred thousand. The signature is then written in the space F, opposite the word "hundreds" in the space H. The numerals are then written in the spaces I, 5 seven opposite the word "hundreds," eight opposite the word "tens," and one seventy-eight one-hundredths opposite the word "units," and ciphers are placed in the other spaces I and K; and, finally, the sum can be written in numerals at the bottom of the check, as illustrated in Fig. 2.

Having thus fully described my invention, I claim as new and desire to secure by Letters Patent—

15 A check, draft, or other money-order made substantially as herein shown and described, with spaces A B C to receive the name of the

place and the date, the name of the drawer and the order and the name of the payee, with a space, D, containing groups of three of each 20 of the digits, with spaces E to receive a statement of the sum in words, with spaces F G to receive the signature of the drawer, and with spaces H I J K corresponding with the spaces F G, the spaces H J containing the names of 25 the various denominations, and the spaces I K to receive numerals representing the amounts of the said various denominations and ciphers, as set forth.

WILLIAM T. DOREMUS.
